ATTORNEY

UNITED STATES PATENT OFFICE.

CHARLES NELSON, OF EAST NEW YORK, N. Y.

SLATE-FRAME.

SPECIFICATION forming part of Letters Patent No. 281,786, dated July 24, 1883.

Application filed March 29, 1883. (No model.)

To all whom it may concern:

Be it known that I, CHARLES NELSON, of East New York, in the county of Kings and State of New York, have invented certain new 5 and useful Improvements in Slate-Frames, of which the following is a specification.

This invention has reference to an improved slate-frame of that class in which is applied around the circumference of the frame a noise- 10 muffling edge-strip, that projects at both sides of the frame; and the invention consists of a slate-frame around the circumference of which is applied a noise-muffling edge-strip composed of an interior core of wood having cords 15 at both edges, the core and the edge-cords being covered by continuous braiding, and then securely attached to the slate-frame.

In the accompanying drawings, Figure 1 represents a side elevation of my improved 20 slate-frame; Fig. 2, an end view; and Fig. 3, a vertical transverse section of the same on line *x x*, Fig. 1.

Similar letters of reference indicate corresponding parts.

25 A represents a wooden slate-frame of the usual construction, that is rounded off at the corners.

Around the entire circumference of the slate-frame A is applied a noise-muffling strip, B, 30 which is composed of a core, *b*, of wood, that is made straight at the side adjoining the outer edge of the slate-frame A, slightly convex at the outer side, and straight at the edges, as shown clearly in Fig. 3. The edges of the 35 strip *b* are provided with edge-cords *b' b'*, which are covered, together with the wooden strip *b*, by a continuous braiding, *d*. The covering of the strip *b* and edge-cords *b' b'* is accomplished on a braiding-machine of that class which is 40 used for braiding whip-stocks and the like.

The strip *b* is made equal in width to the thickness of the slate-frame, the edge cords and braiding causing it to project at both sides of the same, so as to form a support for the slate-frame and produce a muffling and protecting 45 action for the slate. The muffling-strip B is nailed or otherwise fastened to the slate-frame, as shown in Fig. 1, and made of such a length as to extend around the slate-frame, the meeting edges of the strip B being neatly trimmed, 50 so as to fit accurately together. They are then covered by a piece, *e*, of ribbon or other suitable fabric, that is also nailed to the slate-frame, as shown in Figs. 1 and 2.

I am aware that a slate-frame provided with 55 an edge-strip that projects at both sides of the frame is old and has been used heretofore, and I do not claim this feature, broadly.

Having thus described my invention, I claim as new and desire to secure by Letters Patent— 60

1. The combination, with a slate-frame, of a noise-muffling strip, which is applied around the circumference of the frame, and is composed of an interior core or strip of wood having a cord at each edge, said strip and edge-cords being covered by continuous braiding, 65 substantially as set forth.

2. A noise-muffling strip for slate-frames, composed of a core or strip of wood, having a cord at each edge, and of a covering-braid extending continuously over the strip and edge-cords, substantially as set forth.

In testimony that I claim the foregoing as my invention I have signed my name in presence of two subscribing witnesses.

CHARLES NELSON.
